ICE MAKING DEVICE

Paul E. Upchurch, Dayton, Ohio, assignor to General Motors Corporation, Detroit, Mich., a corporation of Delaware

Filed Jan. 25, 1960, Ser. No. 4,354

9 Claims. (Cl. 62—353)

This invention relates to refrigeration and particularly to ice making machines or apparatuses.

Certain types of so-called automatically operating ice block making machines or mechanisms have not been practical or so operable and, therefore, were never produced commercially. Of these machines or mechanisms, there is one in which a mold provided with oppositely facing ice block forming pockets or compartments is rotated for releasing ice blocks therefrom upon application of heat to the mold, such as the heat of incoming liquid to uprighted pockets thereof. A machine or apparatus of this character is shown and described in the patent to H. W. Clum 2,407,058, dated September 3, 1946. In this type of machine or apparatus, a thermally actuated control switch responsive to temperatures of the mold is employed to rotate the mold and is intended to successively invert oppositely facing ice block forming compartments therein. The thermostat control switch is set for actuation to energize an electric motor at a temperature of the mold below freezing which motor causes a rotation of the mold of 180° to ready the ice blocks contained in the inverted compartments thereof for release therefrom. It has been discovered that certain conditions exist or are encountered in an ice block making machine of this type which prevents actuation of the control switch after an initial rotation of the mold in an attempt to discharge ice blocks therefrom. For example, as ice blocks in the inverted pockets or compartments of the mold begin to thaw, in response to warmer liquid entering the uprighted compartments, about or adjacent walls of the inverted compartments, a film of water resulting therefrom and located between the compartment walls and ice blocks therein in contracting in volume thereat, as opposed to water expanding while being frozen, creates a vacuum or water seal between the closed bottom wall of the inverted compartments and the ice blocks. This vacuum tends to suck or hold the ice blocks in the inverted compartments thus delaying or preventing their release therefrom and prolonging a rise in the temperature of the mold by incoming liquid thereto. In such case, the temperature of the control switch is prevented from being timely or quickly increased or warmed sufficiently to open the mold rotating motor circuit for stopping rotation of the mold in a proper water-filling position and the ice blocks refreeze in the pockets or compartments in which they are retained. In other words, a delay in releasing ice block from the inverted compartments will not permit heat of incoming water to the mold to be transferred to the control thermostat switch and this switch is therefore ineffective to stop rotation of the mold. This is a malfunction in the intended automatic operation of an ice block making and releasing machine of the character referred to thereby causing same to become inoperative as such. Thus, after the mold in such a machine has made an initial 180° rotation, in an attempt to have ice blocks removed from pockets thereof, the automatic control of the machine may never be warmed enough to break or open the mold motor rotating electric circuit and stop rotation of the mold. I contemplate the provision of means to overcome this fallacy in ice block making machines or apparatuses of the type herein mentioned, shown and described in the Clum patent referred to, whereby to render the same substantially infallible in automatic operation.

2

An object of my invention is to provide an improvement in an ice block making machine or apparatus which will aid in releasing ice blocks therefrom to thereby insure correct and fully automatic operation thereof.

5 Another object of my invention is to provide a mold for making ice blocks having at least two positions of movement with means whereby, while the mold is in one of its two positions, a body of liquid is retained and frozen therein and which means is effective only when the mold is in the other of its said two positions to vent the interior thereof beneath an ice block contained therein for aiding in releasing the ice block therefrom.

Another object of my invention is to provide means in an ice block manufacturing mechanism for venting the 15 interior of a pocket or compartment of a rotatably mounted or invertible ice block mold of the mechanism to air ambient the mold, upon rotating the mold and inverting the compartment thereof, through one of the compartment interior walls at a point therealong normally contacted by an ice block to prevent the ice block, while it is being thawed, from sticking or hanging up in the compartment whereby its quick release therefrom is assured.

25 Another object of my invention is to provide an automatically operable ice block making machine of the type having a rotatably mounted mold and oppositely facing ice block forming compartments therein with means normally closing a vent in the bottom of uprighted compartments thereof while water is retained and frozen 30 in these compartments which means is rendered effective in response to rotating the mold about its mounting and inverting the ice block containing compartments for opening the vent to air ambient the mold so as to aid in releasing ice blocks therefrom whereby the ice blocks cannot interfere with the automatic operation of the machine.

35 In carrying out the foregoing objects, it is a still further and more specific object of my invention to provide a rotatably mounted ice block forming mold in an ice making device with means associated with or incorporated in 40 the rotary mounting of the mold for venting ice block pockets or compartments thereof as the mold is rotated at a point beneath ice blocks therein for aiding in releasing the blocks therefrom into an ice block harvesting receptacle.

45 Further objects and advantages of the present invention will be apparent from the following description, reference being had to the accompanying drawings wherein a preferred embodiment of the present invention is clearly shown.

50 In the drawings:

FIGURE 1 is a side view partly in elevation and partly in section of a rotatably mounted ice block mold adapted for use in an automatically operated ice maker and showing ice blocks in the upright compartments thereof;

55 FIGURE 2 is a view similar to FIGURE 1 showing the mold rotated with the ice block containing compartments thereof vented and ice blocks releasing from the inverted compartments; and

60 FIGURE 3 is a fragmentary vertical sectional view taken on the line 3—3 of FIGURE 1 showing the compartment vent means in the rotary mounting of the mold.

65 As hereinbefore pointed out, my improvement relates primarily to a mold portion and mounting arrangement therefor in an ice maker which is automatic in operation to freeze liquid in the mold, to rotate the mold and apply heat thereto for releasing ice blocks therefrom and thereafter rerotate the mold to repeat the cycle. Such an ice maker and controls therefor is disclosed in the patent hereinbefore identified and reference to this patent is made to supplement the present disclosure. For all purposes and intent of my invention, the mold and its mounting

herein disclosed may be substituted for the mold and its mounting shown in said patent.

Referring now to the drawings, I show in FIGURE 1 thereof a mold, generally represented by the reference numeral 10, preferably cast of hard aluminum or other good heat conducting material which mold has oppositely facing pockets or compartments 11 and 12 and is provided with a central mounting bore 13. In order to rotatably mount mold 10 in an insulated freezing chamber or the like of a refrigerator or ice maker cabinet, I project a sleeve or hollow shaft 14 into bore 13 of the mold. Sleeve or shaft 14 is stationarily secured at its forward squared end 16 to a mounting bracket 17 in any suitable or conventional manner. The mold 10 is provided at its rear end with an integral cam 18 substantially corresponding to and for the purpose of the cam disclosed in the Clum patent which operates the water valve switch. Mold 10 also has an integral shaft-like extension 19 projecting through a bearing, indicated at 21 and mounted in a well of a boss formed in wall 22 of a cabinet, and provided with a gear 23 secured thereto adapted to mesh with a gear on a shaft of an electric motor (not shown) for successively rotating the mold throughout 180° of rotation about the horizontal axis of sleeve 14. A thermostatic switch 24, substantially corresponding to the control thermostatic switch in the Clum patent for effecting rotation of the mold, is stationarily mounted upon a spring bracket 26 secured to wall 22 of the cabinet and this switch serves to energize the electric motor and rotate mold 10 under temperature changes thereof. Switch 24 is set to close when its temperature is reduced to the point at which water in the mold freezes solid for energizing the mold rotating motor while it remains open above this temperature. Spring bracket 26 biases thermostatic switch 24 against the end of mold 10 so as to maintain the switch in metal to metal contact with the mold and, consequently, responsive to the temperature thereof. The stationary hollow mounting sleeve 14 has spaced apart apertures 31 provided in its annular wall which, like the sleeve, remain stationary as mold 10 is rotated. Suitable means, such as rubber or the like sealing rings 32, are compressed in grooves between the bore 13 of mold 10 and mounting sleeve 14 to prevent liquid received in the mold from seeping outwardly thereof along its mounting. Mold 10 is movable into at least two different positions and the walls of pockets or compartments 11 and 12 are tapered outwardly in the direction of the open end of the compartments. The bottom wall 34 of each of the oppositely facing pockets or compartments 11 and 12 has an opening 36 extended therethrough and this opening in the uprighted compartments 11 is normally closed by the annular wall of sleeve 14 whereby these compartments retain a body of liquid to be frozen therein. Openings 36 are vertically aligned with apertures 31 in sleeve 14 and are adapted to be alternately brought into registration therewith for a purpose to be hereafter described in order that the objects of my invention may be carried out.

The ice making machine or device may be placed in operation as described in the Clum patent until water is flown from a preferably multiple outlet pipe or the like into the individual compartments 11 up to a predetermined measured body of liquid therein. At this time, switch 24 is open and cannot energize the electric motor employed to rotate mold 10. Compartments 11 or mold 10 retain the water received therein, by virtue of the openings 36 thereof being closed by sleeve 14, and this water is adapted to be hard-frozen in the compartments 11 into separated ice blocks. After water in compartments 11 become completely frozen, the temperature of the metal at the rear inverted compartment 12 lowers and at this time thermostatic switch 24 in contact therewith closes. Closing of switch 24 energizes an electric motor having a gear on its shaft meshing with gear 23 to rotate mold 10 approximately 180° about its stationary mounting, sleeve 14, to simultaneously invert the ice block containing compart-

ments 11. As compartments 11 are inverted, the oppositely facing compartments 12 are uprighted (see FIGURE 2) and substantially filled with a body of liquid entering the mold from exteriorly of the chamber in which it is mounted. The heat of this incoming above-freezing temperature liquid or water is adapted to be quickly conducted by the metallic mold 10 to walls of the inverted ice block containing compartments 11. The water contained in the now uprighted compartments 12 is above freezing and its heat is applied to ice blocks positioned in the inverted compartments 11. It is to be noted that the rotation of mold 10 has rotated and brought openings 36 in the bottom wall 34 of compartments 11 into aligned registration with the apertures 31 in the annular wall of stationary sleeve 14. As the heat of water in uprighted compartments 12 is absorbed by ice blocks in the inverted compartments 11, the ice blocks thaw and melt a thin film of water along the surface of the compartments, and since the compartments are now vented at a point therealong normally contacted by ice blocks therein to air ambient mold 10, the ice blocks quickly fall from compartments 11 by gravity into a storage or harvesting receptacle below mold 10. By virtue of venting the inverted ice block compartments as herein shown and described and causing immediate release of thawed ice blocks therefrom, the heat of water contained in the uprighted compartments 12 is rapidly conducted to thermostat switch 24. Since mold 10 is now devoid of ice blocks, their temperature cannot affect switch 24 to delay actuation thereof and this switch is warmed by the mold to open the mold rotating motor circuit and stop rotation of the mold at its proper water-filling position. With the ice blocks being aided in releasing from the inverted compartments 11 as explained to positively cause opening of thermostat switch 24, this switch must, in order to be actuated closed for rotating mold 10, await a reduction in temperature of the mold below a water freezing temperature. After ice blocks are completely frozen in the uprighted compartments 12, the below freezing temperature of mold 10 is conducted to switch 24 and this switch is again closed to cause a subsequent rotation of the mold for releasing ice blocks from its compartments 12. The accumulation of ice blocks in a receptacle below mold 10 may be utilized to discontinue operation of the automatically operated mechanisms as shown and described in the Clum patent to stop production of ice blocks in the ice maker device until such time as more ice blocks are desired.

It should, from the foregoing disclosed mold compartment venting arrangement, be apparent that I have made an improvement invention without which certain types of so-called automatically operated ice block making machines or apparatuses are or will, upon being put into operation, become inoperable as such. My invention therefore overcomes a fallacy in certain published ice making device disclosures and renders them practical and fully automatic in operation whereby they may attain a reality instead of a mere disclosure. The ice block venting arrangement herein disclosed is applied to mold compartment walls at a point therealong normally contacted by ice blocks therein as distinguished from ice blocks in mold compartments exposed at the open end of the compartments to air ambient a mold as is conventional. In this respect, I have provided a vent in a mold compartment wall which is closed while the mold is in one of two movable positions thereof, so as to retain liquid adapted to be frozen therein into an ice block, and which vent is effective only when the mold is moved into the other of its two positions of movement for aiding in releasing an ice block from its compartment. While I have set forth my invention as pertaining to one type of ice making machine or mechanism, it is to be understood that aiding in the release of ice blocks from their compartments, in response to rotating a mold and venting the compartments, may have a wide or diversified use in the art.

While the embodiment of the present invention as here-

in disclosed, constitutes a preferred form, it is to be understood that other forms might be adopted.

What is claimed is as follows:

1. An ice making device comprising, a rotatably mounted mold having oppositely facing compartments, means for rotating the mold about its mounting to successively bring said compartments into position to receive liquid and to have the liquid received in one of said compartments frozen into an ice block, said one compartment being inverted by said rotating means to ready the ice block releasable therefrom by liquid received in the other of said oppositely facing compartments, and means rendered effective by the inversion of said one compartment for venting the interior thereof through one of its walls at a point therealong contacted by the ice block therein to air ambient the mold for aiding release of said ice block from said one compartment.

2. An ice making device comprising, a rotatably mounted mold having oppositely facing compartments, means for rotating the mold about its mounting to successively bring said compartments into position to receive liquid and to have the liquid received in one of said compartments frozen into an ice block, said one compartment being inverted by said rotating means to ready the ice block releasable therefrom by liquid received in the other of said oppositely facing compartments, and means within the rotatable mounting of said mold rendered effective by the inversion of said one compartment for venting the interior thereof through one of its walls at a point therealong contacting the ice block therein to air ambient the mold for aiding release of said ice block from said one compartment.

3. In combination, a mold having a compartment for receiving a body of liquid adapted to be frozen within the compartment into an ice block, means for rotatably mounting the mold, said means comprising a stationary anchored sleeve projected into a bore provided in the mold and about which said mold is to be rotated, at least one end of said sleeve being exposed to air ambient the mold, said sleeve having an aperture in its annular wall located opposite said mold compartment, the wall of said compartment adjacent the bore in the mold being provided with an opening extending therethrough normally closed by said sleeve wall and adapted to be brought into registration with the aperture therein, and means for rotating said mold about said mounting means to substantially invert said compartment and shift the opening in its wall into alignment with the aperture in said annular wall of said stationary sleeve to vent the compartment at a point contacted by the ice block therein to thereby aid in releasing said ice block therefrom.

4. An ice making device comprising, a rotatably mounted mold having a compartment for receiving a body of liquid to be frozen within the compartment into an ice block, means for rotating the mold about its mounting to invert said compartment and ready the ice block for release therefrom, and means within the rotatable mold of said mold rendered effective by the inversion of said compartment for venting the interior thereof through a wall of the compartment at a point therealong contacting the ice block therein to air ambient the mold for aiding release of said ice block from the device.

5. A mold having oppositely facing compartments one of which receives water adapted to be frozen in said one compartment into an ice block, means for rotatably mounting said mold, said mounting means comprising a stationary anchored sleeve projected into a bore provided in the mold intermediate said compartments and about which said mold is to be rotated, at least one end of said sleeve being exposed to air ambient the mold, said sleeve having

an aperture in its annular wall located opposite said one of the oppositely facing compartments, the wall of said compartments adjacent the bore in the mold each being provided with an opening extending therethrough, the opening in said one compartment wall normally being closed by said sleeve wall and adapted to be brought into registration with the aperture therein, means for rotating said mold about said mounting means to substantially invert said one compartment and rotate the other of said oppositely facing compartments into a water receiving position, and the rotation of said mold shifting the opening of said one compartment wall into alignment with the aperture in said annular wall of said stationary sleeve to vent said inverted compartment through its normal bottom wall contacted by the ice block therein to thereby aid in releasing said ice block therefrom.

6. A movable mold adapted while in one position to receive and retain a body of liquid to be frozen into an ice block therein and adapted to be shifted out of said one position into another position, means rendered effective solely by shifting the mold from said one position to said another position for venting the interior of said mold through a wall portion thereof contacted by the ice block before breaking a bond between said ice block and the mold, and the venting of said mold with the ice block bonded therein then aiding release of said ice block from walls of the mold.

7. A movable mold adapted while in one position to receive and retain a body of liquid to be frozen into an ice block therein and adapted to be shifted out of said one position into another position, means rendered effective only as and solely by shifting the mold from said one position to said another position for venting the interior of said mold through a wall portion thereof contacted by the ice block before breaking a bond between said ice block and the mold, walls of said mold being adapted to be warmed after the mold has been so shifted, and the venting of said mold with the ice block bonded therein aiding release of said ice block from walls of the mold when they are warmed.

8. A mold mounted for rotation into at least two positions and adapted to receive and retain a body of liquid in one of said positions to be frozen into an ice block therein, means for rotating said mold into the other of its said two positions, means rendered effective solely by the rotation of said mold into said other position for venting the interior thereof through one of its walls contacted by the ice block before breaking a bond between said ice block and the mold, and the venting of said mold with the ice block bonded therein then aiding release of said ice block from walls of the mold.

9. An ice making device comprising, a rotatably mounted mold having a compartment for receiving and retaining a body of liquid to be frozen therein into an ice block, means for rotating the mold about its mounting to invert said compartment, means rendered effective solely by the rotation of said mold for venting the interior of said compartment through a wall thereof contacted by the ice block before breaking a bond between said ice block and the compartment, and the venting of said inverted compartment with the ice block bonded therein then aiding gravitational release of said ice block from walls of the compartment.
